UNITED STATES PATENT OFFICE.

PETER C. PATTERSON, OF MCKEESPORT, PENNSYLVANIA, ASSIGNOR TO THE NATIONAL TUBE COMPANY, OF NEW YORK, N. Y.

TOOL FOR CHARGING PLATES INTO FURNACES.

SPECIFICATION forming part of Letters Patent No. 660,198, dated October 28, 1900.

Application filed June 28, 1900. Serial No. 21,888. (No model.)

To all whom it may concern:

Be it known that I, PETER C. PATTERSON, a resident of McKeesport, in the county of Allegheny and State of Pennsylvania, have 5 invented a new and useful Improvement in Tools for Charging Plates into Furnaces; and I do hereby declare the following to be a full, clear, and exact description thereof.

My invention relates to tools for handling 10 plates in furnaces, and more particularly to tools for forcing heated plates from furnaces into rolls, such as in forcing plates into scarfing-rolls to be scarfed previous to being bent into skelp for the manufacture of tubing. 15 Its object is to provide a simple and convenient tool by which the heavy labor of forcing the plates from the furnace is overcome, and the movement of the incoming plate next to be heated into the furnace is utilized in forcing 20 the heated plate forward into the rolls.

The invention consists, generally stated, in a tool having at its forward end a tongue to pass under the heated plate to be forced from the furnace, a shoulder to bear against the 25 rear end of that plate, and a shoulder back of the same to engage with any suitable moving body, such as the entering plate next to be heated, which forces both the tool and the heated plate through the furnace and the 30 plate into the rolls or other engaging means.

It also consists in certain other improvements, to be hereinafter described and claimed.

To enable others skilled in the art to make 35 and use my invention, I will describe the same more fully, referring to the accompanying drawings, in which—

Figures 1 and 2 are perspective views of different forms of the tool embodying the invention. Fig. 3 is a diagrammatic sectional view of a furnace, rolls, and pushing mechanism, illustrating the use of the invention; and Fig. 4 is a diagrammatic horizontal section on the line 4 4, Fig. 3.

45 It has been customary heretofore in heating wide heavy plates for forming tubing to feed them one by one through the furnace, the furnace-hearth in some cases being wide enough to receive more than one plate, in 50 which case the charging mechanism and the rolls to receive and roll the scarfs or bevels

on the edges of the plates are either made laterally movable or are duplicated for receiving the plates from the different parts of the furnace. The plants comprise a suitable 55 pushing or charging mechanism for forcing the plate into the furnace, which usually has a solid brick bottom, and rolls at the opposite end of the furnace into which the heated plates are pushed and which after receiving 60 a plate draw it from the furnace, the draft of the rolls carrying the plate at a somewhat greater speed than the speed at which it is fed into the furnace. For the purpose of pushing the heated plates from the furnace it 65 has heretofore been necessary to employ long charging-forks, operated either by hand or connected to the pushing mechanism. The power-operated mechanism has been found cumbersome, while the hand-operated pushing-forks of course required considerable 70 labor.

According to the present invention by the employment of a simple tool the machines are relieved of the long pushing-forks, while 75 all heavy hand-labor is done away with. The forks employed, as shown in Figs. 1 and 2, are simply long bars, the body portions 1 of which are usually made from fourteen to sixteen feet in length to provide for the travel of the 80 bar into the furnace a sufficient distance to feed the heated plate into the rolls without permitting the rear ends of the bar having the handles 2 to enter the furnace. At the opposite side or front end of the bar is a head 85 3, the lower portion of which extends downwardly, being provided with a tongue which is adapted to pass under the heated plate until the shoulder 5 on the front side of the head 90 3 bears against the rear edge of the heated 95 plate, while through the head 3 the bar is held up above the bottom of the furnace, the rear shoulder or face 6 being in the course of the entering plate next to be heated and as that plate is being pushed into the furnace 95 transmitting the motion from the plate to the heated plate to force it into the rolls. The shoulders 5 and 6 may either be made practically square or, as preferred by me and as illustrated in Fig. 2, may be made receding, as illustrated in Fig. 1—that is to say, the upper edge 7 of the front shoulder 5 pro-

jects forward of the lower portion or bearing-face 8 thereof, while the lower edge 9 of the rear shoulder 6 projects backwardly from the portion 10 close to the body 1 of the tool. 5 Such construction overcomes all liability of either the heated plate riding upwardly and passing over the top of the tool or of the cold entering plate slipping under the tool. The side faces 11 of the head 3 are made 10 straight, as shown, and connected by inclines 12 with the body 1, so that when the tool is turned a quarter around the entering plate being fed to the furnace will naturally slip under it and permit the withdrawal of the 15 tool.

In the mechanism illustrated in the drawings, with which the tool is to be used, the feeding-table 13 stands in front of the furnace, the plate to be charged resting upon 20 this table, while a pushing jaw or arm 14, operated by suitable power mechanism, engages with the rear end of the plate and forces it into the furnace 15, the plates resting upon the hearth 16 of the furnace. In front of this 25 furnace are the scarfing-rolls 17, which are driven at suitable speed, it being preferred that the speed shall be greater than the speed of the pushing-arm 14, so that when the plate engages with the rolls it will be drawn from 30 the tongue of the charging-tool.

In the operation of the furnace with the use of the tool the first plate to be heated is placed upon the table 13, and by means of the power-operated pushing-jaw 14 the plate is 35 pushed upon the hearth and rests there until it is raised to proper heat for rolling and sending into skelp. The operator then slips the tongue 4 of the tool under the rear end of the heated plate, bringing the shoulder or 40 pushing-face 5 into contact with the rear edge thereof, and by means of the handle 2 he holds the plate in this position while the next plate resting on the charging-table 13 is engaged by the power - operated jaw 14 and 45 pushed into the furnace, and the front edge of this plate so being pushed into the furnace contacts with the rear face of the shoulder 6 of the tool and through the same forces the tool and the heated plate forward in the furnace until the heated plate engages with the 50

rolls or is engaged by any other carrying means, when the operator by simply giving the tool a quarter-turn brings one of the inclines 12 into line with the front edge of the entering plate, when that plate passes under 55 the tool and leaves the tool free to be withdrawn.

In so charging the plates the only labor necessary is to pass the tool into the furnace and under the heated plate and to hold the 60 tool in position until that plate is fed to the rolls and then withdraw the tool, the heavy labor being all performed by the entering plate. It is evident, of course, that the tool might provide in the same way for contact 65 with any moving body and impart its force to the plate to be forced from the furnace.

What I claim as my invention, and desire to secure by Letters Patent, is—

1. A tool for forcing plates from furnaces, 70 having at its front end a tongue to pass under the plate, a shoulder to bear against its rear edge and another shoulder back of the same to engage with a pushing device.

2. In a tool for forcing plates from 75 furnaces, having at its front end a tongue to pass under the plate, a receding shoulder to bear against its rear edge and another shoulder back of the same to engage with the pushing device.

3. A tool for forcing plates from furnaces, having at its forward end a tongue to pass under the plate, a shoulder to bear against its rear edge, and a receding shoulder back of the same to engage with a pushing device. 85

4. A tool for forcing plates from furnaces, having at its front end a head provided with a tongue to pass under the plate, a shoulder to bear against its rear edge and another shoulder back of the same to engage with the 90 pushing device, the body of the tool being connected with side portions of said head by inclines.

In testimony whereof I, the said PETER C. PATTERSON, have hereunto set my hand.

PETER C. PATTERSON.
